UNITED STATES PATENT OFFICE.

ANSON P. BOARDMAN, OF WATERTOWN, WISCONSIN.

POLISHING-MACHINE.

SPECIFICATION forming part of Letters Patent No. 445,030, dated January 20, 1891.

Application filed April 7, 1890. Serial No. 346,811. (No model.)

To all whom it may concern:

Be it known that I, ANSON P. BOARDMAN, of Watertown, in the county of Jefferson and State of Wisconsin, have invented new and useful Improvements in Polishing-Machines; and I do hereby declare the following to be a full, clear, and exact description of said invention, reference being had to the accompanying drawings, and to the letters or figures 10 of reference marked thereon, which form a part of this specification.

My invention relates particularly and chiefly to the means for adjusting the feed-rollers, for supporting and adjusting the upper feed-15 roll carrying-frame, and to the devices for vibrating the polishing-cylinders.

My improvements are in that class of polishing-machines which have sand-paper-covered cylinders located and arranged in the 20 lower or body part of the machine.

In the drawings, Figure 1 is a side elevation of my complete device, the lower portion of the frame being omitted for convenience of illustration. Fig. 2 is an end view 25 of the same machine, the lower portion of the frame being omitted. Fig. 3 is a plan of a journal-bearing of a feed-roll and of related mechanism for adjusting it and the supporting-frame. Fig. 4 is an elevation or side view 30 of the same journal-bearings shown in Fig. 3, with mechanism for adjustment of the upper frame. Fig. 5 is a detail showing the bearing of a journal of a sand-cylinder and devices related thereto, partly in vertical section, for 35 adjusting the journal-bearing and for vibrating the cylinder. Fig. 6 is a plan of so much of the mechanism shown in Fig. 5 as is below the line 6 6 thereof, with related mechanism, parts being broken away and in section to 40 show interior construction.

A is the frame of the machine, which includes an upper portion A', supported above the lower or body part of the frame by rigid angled corner-posts C C, constructed integrally with the frame or made rigid thereto.

B is a frame carrying the upper feed-rollers, which frame is supported movable vertically below the part A' and at a distance from the body of the frame A.

50 Three sand-paper-covered polishing-cylinders D D D, arranged transversely to the

longer axis of the machine, are supported in journal-bearings adjustably in the frame A. The number of cylinders used in a machine may be one or more; but it is desirable to use 55 at least three cylinders to secure the best results. These cylinders are so located in the frame that the surface of the cylinder at its top projects slightly above the top surface or table of the frame A throughout the entire 60 length of the cylinder. The journals 10 of these cylinders have their bearings in boxes 11 11, each of which is provided with a rigid downwardly-extending leg 12, which enters, 65 movably, a projecting part 13 of the frame, in and by which it is guided in its slight vertical movement. The leg 12 terminates in a continued screw-threaded bolt 14, fixed in the leg 12 or made integral therewith, on which bolt a screw-threaded nut 15 turns, which nut 70 bears above and below against the part 13 of the frame. The nut 15 has a worm-toothed periphery which meshes with a worm 16, fixed on shaft 17. The shafts 17 each have their bearings at both ends eccentrically in cylindrical blocks 18, which blocks 18 have their 75 bearings rotatably in the frame A. The blocks 18 are provided with pin-holes 19 19, adapted to receive a pin-wrench thereto for rotating them, and a set-screw 20 turns through the frame 80 against the block 18 to lock it in position when adjusted. By thus supporting the shafts 17 eccentrically in adjustable blocks 18 18 at both ends the shafts are adjusted at each end independently and a perfect alignment secured. The shafts 17 17 are each provided with a beveled gear 21, meshing with a beveled gear 22, fixed on a short vertical shaft 23, which shaft 23 has its bearings in a bracket 24, integral with frame A. The shaft 90 23 is faced at 25 to permit of the application of a wrench thereto for rotating it. By rotating a shaft 23 the corresponding cylinder may be raised or lowered, and should it be necessary to raise one end of the cylinder independently of the other end for the purpose of alignment the shaft 17 may be thrown away from the nuts 15 by rotating the blocks 18, and by turning the nuts 15 either up or down the respective ends of the cylinders are 95 raised or lowered. The cylinders are each driven independently of the other by a band- 100

wheel 26, fixed on its shaft, the band-wheel of the middle cylinder being located farther from the frame of the machine than the band-wheels on the other two shafts for the clearance of the belts.

For accomplishing the endwise vibration of the cylinders, a ring 27 rides on each shaft 10 between two collars 28 28, fixed to the shaft by set-screws, which ring is provided with a rigid pin 29, which projects into a diagonal slot 30 in the arm 31. The rocking arm 31 is pivoted on a headed pin 32, fixed in the part 13 of the frame. The pin 32 is hollow longitudinally and is provided with a sliding block 33, a part of which projects into a longitudinal slot 34 in the pin 32, and the pin 29 enters loosely the sliding block 33, which serves as a guide to steady and control the pin 29. An anti-friction bearing-sleeve 35 is placed about the pin 29 in the diagonal slot 30. The pin 32 is secured in the frame by a rivet 36. A set-screw or other equivalent means may be used for this purpose. The rocking arms 31 31 are each connected movably to a connecting-rod 37 by a wrist-pin 38, and the rod 37 is hinged to a pitman 39, which rides on an eccentric 40, fixed on a shaft 41, having its bearings in brackets affixed to the frame, which shaft is provided with a band-wheel 42, through which it is driven.

Feed-rollers 43 43, alternating with the sand-cylinders, are located in the frame A, and other feed-rollers 44 44 are located in the frame B directly above and parallel to the rollers 43. To provide for the adjustment or alignment of these feed-rollers independently of each other and at each end, the rollers are all journaled at both ends eccentrically in cylindrical blocks 45 45. These blocks have their bearings rotatably in the frame A and B, respectively, and are each provided with pin-wrench holes 46 46 for rotating them, and set-screws 47 47 are provided, turning through the frame against the blocks severally for locking them in position when adjusted. The journals of the feed-rollers 43 43 are provided with beveled gears 48 48, which mesh with beveled gears 49 49 on the horizontal shaft 50, which shaft 50 has a gear meshing with a gear on the vertical shaft 51, which is geared to the horizontal shaft 52, which is provided with a band-wheel 53, through which it is driven, and the feed-rollers are rotated. The journals of the rollers 44 44 are also provided with beveled gear 54, which mesh with beveled gears 55 55 on horizontal shaft 56, which shaft 56 is geared to vertical shaft 57, which shaft 57 is geared to the shaft 52, by which it is driven and through which the rollers 44 44 are driven. The shaft 56 is geared to the shaft 57 by and through a sleeve 58, feathered and movable endwise on the shaft 57, which sleeve is provided with the gear which meshes directly with the gear on shaft 56 and is supported and rotates in a bracket on the frame. The shafts 50, 51,

52, 56, and 57 have their bearings in brackets on the frames A and B, respectively. Four screw-threaded vertical adjusting-rods 59 59, one at each corner of the machine, have their feet severally movable in bearings therefor in the frame of the machine and extend upwardly through the part A', being provided at the top with gears that mesh with gears on the horizontal shafts 60 60, having their bearings in brackets therefor affixed to the frame, one of the shafts 60 being provided with a crank-handle 61 for rotating them, and thereby rotating the adjusting-rods 59 59. Each of these rods 59 is provided with a square-headed sleeve-nut 62, traveling thereon, the head of which nut is received and guided in its vertical movement by the walls of the post C, whereby the sleeve-nut is held against rotary movement.

The frame B is provided at its four corners with horizontally-projecting lugs 63, having a vertical aperture through which the shank of the sleeve-nut 62 is received, the lug 63 resting on the head of the nut 62, whereby the frame B is supported. A spring 64 is coiled about the nut 62 and bears at its lower end against the lug 63 and at its upper end against a nut 65, turning by screw-thread on the sleeve-nut 62. The nut 65 is provided with apertures for receiving a pin-wrench thereon for rotating it. The frame B is thus supported movably on the heads of the adjustable sleeve-nuts 62 62 and is movable thereon vertically, the springs 64 64 being adapted to permit a slight amount of yielding upwardly to the frame B under considerable strain. The frame B is raised or lowered by rotating the rods 59 59 through the crank-handle 61 and shafts 60 60.

Three transverse presser-plates 66 66, presenting their faces downwardly about in a plane with the lowest part of the feed-rollers 44 44, are hinged at one side on the frame B, whereby they are adapted to be swung upwardly away from their normal position, (shown in Fig. 1,) if desired. These presser-plates are constructed to act by gravity only and are adapted to bear against the material being operated on directly above the sand-paper cylinders, and thereby obviate the slight vibration or quivering of the material that might otherwise occur.

What I claim as new, and desire to secure by Letters Patent, is—

1. In a polishing-machine having rotating polishing-cylinders, the device at each end of the cylinders for adjusting them vertically, consisting of a leg extending rigidly downwardly from each of the journal-boxes, which leg is received and guided in a part of the frame arranged therefor, a screw-threaded bolt extending rigidly downwardly from and as a continuing part of the leg, and a nut turning thereon, which nut bears movably above and below against the frame, substantially as described.

2. In a polishing-machine having rotating

polishing-cylinders, the combination, with legs extending downwardly from the journal-boxes of the cylinders, which legs are provided with screw-threaded bolts, and nuts 5 turning thereon bearing above and below against the frame, of a shaft provided with a worm meshing with teeth on the nut on the bolt aforesaid, which shaft has its bearings eccentrically in rotatable cylinders in the frame, and means for rotating the shaft, substantially as described.

3. In a polishing-machine having polishing-cylinders provided with bearings permitting endwise movement, and a ring riding on the 15 journal of the cylinder and having rotary but not endwise movement thereon, which ring is provided with an outwardly-projecting pin, in combination with a rocking arm pivoted on the frame and provided with a diagonal slot 20 in which the pin on the ring is received and by which it is moved as the rocking arm oscillates, and means, substantially as described, for oscillating the arm.

4. In a polishing-machine having a polishing-cylinder so journaled as to be movable endwise, and a ring riding rotatably on the journal of the cylinder and provided with a projecting pin, in combination with a rocking arm having a diagonal slot, which arm is pivoted on a hollow longitudinally-slotted pin affixed to the frame, a sliding block inserted and traveling in the hollow pivot-pin, into which block the pin on the ring enters and by which it is steadied, and means, substantially as described, for oscillating the rotating arm.

5. In a machine having transverse feed-

rollers, cylindrical blocks in which the feed-rollers are journaled eccentrically, the blocks being supported rotatably in the frame and 40 provided with means for rotating them limitedly, the blocks being adapted to adjust the feed-rollers vertically, substantially as described.

6. In a polishing-machine, a feed-roller having 45 projecting journals, in combination with cylindrical blocks in which the journals have their bearings eccentrically, the blocks being supported rotatably in the frame, and a set-screw turning through the frame against 50 the block for locking it in position, substantially as described.

7. In a polishing-machine having transverse polishing-cylinders in the lower or body part of the frame, and a vertically-moving frame located above the body of the frame, in combination with vertical screw-threaded adjusting-rods having rotary but not endwise movement in the frame, headed nuts having screw-threaded sleeves traveling on the adjusting- 55 rods, the nuts being held against rotation by ways in the frame, on which nuts the vertically-moving frame is supported, and springs coiled about the sleeves of the nuts, bearing 60 against the frame and against other nuts 65 turning on the sleeves of the traveling nuts, substantially as described.

In testimony whereof I affix my signature in presence of two witnesses.
